(57) **CLAIM**

The ornamental design for conveyor machine as shown and described.

DESCRIPTION

The patent or application file contains at least one drawing executed in color. Copies of this patent or patent application publication with color drawing(s) will be provided by the Office upon request and payment of the necessary fee.

1. Conveyor machine

1.1: a perspective view of the conveyor machine;

1.2: a front view of the conveyor machine;

1.3: a right view of the conveyor machine;

1.4: a back view of the conveyor machine;

1.5: a left view of the conveyor machine;

1.6: a top view of the conveyor machine;

1.7: a bottom view of the conveyor machine.
